UNITED STATES PATENT OFFICE

102,295

DESIGN FOR A SIGN OR SIMILAR ARTICLE

Jose Trojan, Chicago, Ill., assignor to Owen Heusholder and David C. Cohen, a copartnership, doing business as Crystal Manufacturing Co., Chicago, Ill.

Application October 22, 1936, Serial No. 65,424

Term of patent 3½ years

To all whom it may concern:

Be it known that I, Jose Trojan, a citizen of the United States, residing at Chicago, in the county of Cook and State of Illinois, have invented a new, original, and ornamental Design for a Sign or Similar Article, of which the following is a specification, reference being had to the accompanying drawing, forming part thereof.

Figure 1 is a perspective view of a sign or similar article embodying my new design;

I claim:

The ornamental design for a sign or similar article as shown.

JOSE TROJAN.
